UNITED STATES PATENT OFFICE.

GEORGE ARTHUR ERRINGTON, OF TORONTO, ONTARIO, CANADA.

SWITCH-POINT DRAIN-BOX.

1,136,782.

Specification of Letters Patent.

Patented Apr. 20, 1915.

Application filed June 15, 1914. Serial No. 845,151.

To all whom it may concern:

Be it known that I, GEORGE ARTHUR ERRINGTON, of the city of Toronto, in the county of York, in the Province of Ontario, 5 Canada, have invented certain new and useful Improvements in Switch-Point Drain-Boxes, of which the following is the specification.

My invention relates to improvements in 10 switch point casings and drain boxes therefor and the object of the invention is to devise means whereby all moisture and foreign 15 matter may be drained off from the switch point casing and conduits containing the switch point mechanism and whereby water so collected is carried off to the sewer and the foreign matter retained in the drain box so as to be easily removable therefrom and it consists essentially of a Y-shaped rail section 20 forming the switch point casing having an open center and cross bars extending across such open center and a switch point swingably supported thereon, a boxing extending below the switch point casing and 25 having an inclined bottom provided with an opening in the side wall of the casing in the lowest point in the casing, an inlet orifice extending into the casing and leading from the conduit containing the switch operating 30 mechanism and a concave sieve removably supported within the boxing and extending from end to end of the same intermediately of its height as hereinafter more particularly explained by the following specification.

Figure 1, is a general plan view showing the location of my drain box in relation to the conduits containing the switch operating mechanism and with the cover thereof removed. Fig. 2, is an enlarged plan view 40 of the drain box as shown in Fig. 1. Fig. 3, is a cross sectional view on line $x-y$ Fig. 2. Fig. 4, is a longitudinal section through Fig. 2, on line $x'-y'$ Fig. 3.

In the drawings like letters of reference indicate corresponding parts in each figure.

A is one of the track rails.

A' is a substantially Y-shaped rail section, such section comprising the arms A² and A³ 50 and having an intervening open portion A⁴. This open portion A⁴ extends from the diagonal line A¹¹ on one side to the edge of the rail A' on the other and from the inner edge of the drain box A¹² on the right of 55 Fig. 2 to the line A¹³ on the left. Across

this open portion A⁴ extends the cross bar A⁵. The arms A² and A³ are provided with side openings A⁶ and A⁷ divided by vertical bar members A⁸.

A⁹ is a switch point pivotally supported 60 on one of the cross bars A⁵ by a suitable bolt A¹⁰.

B are conduits containing the operating mechanism for operating the switch point. I do not describe this as it forms the subject 65 matter of a co-pending application filed of even date herewith.

6 is a slot formed in the switch point in proximity to its free end and through which the switch point lever 7 extends.

8 and 9 are pins extending through the lever 7 at each side of the switch point thereby connecting the switch point and lever together.

C is the drain box proper provided with 75 an inclined bottom C', (see Fig. 3), outlet opening C² and inlet opening C³.

C⁴ is a supplemental duct (see dotted lines Fig. 1) connecting the conduits B with the inlet orifice C³.

I preferably form my drain box with a 80 dividing partition D having a concave upper face.

D' and D² are sieve frames provided with suitable sieves, the frames also being formed 85 concaved in cross section. The sides of the sieves rest upon lugs E and E' extending inwardly from the sides of the drain box.

F is a removable cover for the drain box.

It will thus be seen that any water which 90 may collect in the conduits B will pass through the supplemental duct C⁴ (see dotted line Fig. 1) through the inlet orifice C³ on to the sieve D², any solid matter passing through the inlet being caught by the 95 sieve. The water which passes through the sieve passes down the inclined bottom and is drained out through the outlet orifice C² into a suitable channel leading to the sewer. Any water which passes into the casing containing the switch point passes through the 100 openings between the cross bar A⁵. Any chips or other solid foreign matter which passes with the water through the switch point casing is also caught by the sieves D² 105 and D'.

H are cross bolts which extend through the switch point casing and through the slots H' in the switch point thereby preventing 110 vehicle wheels passing downwardly between

the switch point and the rail and being caught therein, such vehicle wheels riding upon the cross bolts H.

I have made my sieves convex in cross section so as to permit of their free withdrawal from the drain box through the space between the switch point casing and the side of the drain box. It will be readily seen that if the sieves were made flat instead of convex it would be more difficult to accomplish their easy withdrawal.

From this description it will be seen that I have devised a very simple form of switch point casing and drain box which will carry off all moisture from the switch point and conduits containing the switch point operating mechanism and which will prevent the clogging of foreign matter between the switch point and rail and which will permit of the easy withdrawal of any solid foreign matter which is retained in the drain box.

What I claim as my invention is.

1. The combination with a Y-shaped rail section having an open bottom and adapted to support a swingable switch point, of a drain box surrounding the switch point casing and extending beneath the same and having an inclined bottom and an outlet orifice extending through the wall of the

casing at the lowest point of the incline, and removable screens supported within the drain box beneath the switch point casing, as and for the purpose specified.

2. The combination with a Y-shaped rail section having an open bottom and adapted to support a swingable switch point, of a drain box surrounding the switch point casing and extending beneath the same and having an inclined bottom and an outlet orifice extending through the wall of the casing at the lowest point of the incline, and removable screens removably supported within the drain box casing and formed concave in cross section, as and for the purpose specified.

3. The combination with the switch point casing and conduits containing the switch point operating mechanism, of a drain box having an inlet orifice leading from the aforesaid conduits, an inclined bottom and having an outlet orifice extending through the wall of the casing at the lowest point in such inclined bottom, as and for the purpose specified.

GEORGE ARTHUR ERRINGTON.
